UNITED STATES PATENT OFFICE.

WILLIAM LYON AND JOHN B. GORRELL, OF LA OTTO, INDIANA.

DEVICE FOR PREVENTING THE DEPRESSION OF RAILWAY-RAIL JOINTS.

SPECIFICATION forming part of Letters Patent No. 375,423, dated December 27, 1887.

Application filed September 19, 1887. Serial No. 250,085. (No model.)

To all whom it may concern:

Be it known that we, WILLIAM LYON and JOHN B. GORRELL, citizens of the United States, residing at La Otto, in the county of 5 Noble and State of Indiana, have invented certain new and useful Improvements in Devices for Preventing the Depression of Railway-Rail Joints; and we do declare the following to be a full, clear, and exact description of the invention, such as will enable others skilled in the art to which it appertains to make and use the same.

This invention has relation to improvements in devices for sustaining and adjusting the 15 meeting ends of railway-rails, and the novelty will be fully understood from the following description and claims, when taken in connection with the annexed drawings, in which—

Figure 1 is a perspective view of a portion 20 of a rail, showing our improvements attached to the ties. Fig. 2 is a plan view of a portion of a rail, showing our improvements attached to the ties. Fig. 3 is a longitudinal sectional view taken on the lines *x x* of Fig. 2. Fig. 4 is a sectional view taken on the lines *y y* of Fig. 2. Fig. 5 is a view of the yoke removed, and Fig. 6 is a perspective view of the wear-plate removed.

Referring by letter to the said drawings, A 30 indicates a series of railway cross-ties.

D indicates two sections of a railway-track, the joints or meeting ends of which are shown at E. To provide against shrinkage and depression of said meeting ends and for adjusting the same when depressed, we provide a sustaining metallic bridge, F, and secure the ends thereof, by bolts or spikes, to the respective cross-ties that are arranged on the right and left hand sides of the tie upon which the rails 35 meet, as shown. This metallic bridge F is concave on its under surface and convex on its upper surface longitudinally, and is provided with openings *a a*, the upper portions of which are enlarged to receive screw-nuts *c*, as shown.

G represents a yoke, which consists of a 45 strong rod of iron or steel bent in the form shown, and having its upper or free ends provided with screw-threads to receive the nuts *c*, in the manner shown on Fig. 3 of the drawings.

H represents a metallic shoe or wear-plate, which is passed under the cross-tie upon which

the rails meet, and when thus arranged is clasped by the closed end of the yoke. The arms of said yoke are passed upward through 55 the metallic bridge F and made secure in position by the nuts *c c*.

When the several parts are arranged as described, it is obvious that by turning the nuts *c* on the threads of the yoke the tie immediately under the joints of the rails can be operated so as to raise and adjust said joints at will. It should be here observed that this metallic bridge is sprung upward longitudinally for the greater portion of its length, and that 65 the vertical apertures are formed in the elevated or spring portion thereof. Thus it will be seen that there will be sufficient room beneath this bridge for the rise and adjustment of the tie upon which the meeting ends of the 70 rails rest. It will also be seen that when a tie has been properly adjusted so as to bring the meeting ends of the rails in the desired position there is little or no liability of the tie going down or the rail-joints depressing as 75 long as the nuts and yoke remain unimpaired, as it is obvious that the bridge must yield longitudinally before a sag or depression will take place. It is also obvious that our improvements might be applied to old roads or 80 rails as well as new ones.

In applying our improvements to old roads where the meeting ends of the rails have become depressed after adjusting the yoke, we turn up the nuts a few times on the threaded 85 ends thereof until the ties beneath their joints have been raised to the proper height, which, of course, will raise the joint of the rails, the concavity beneath allowing ties of irregular form to rise to the desired elevation, consequently requiring no care whatever in leveling the upper surface of the ties to adjust the bridge.

Another feature of construction to which we attach importance is the pin or stud in the 95 stringers or beams, as it will be seen that while the tie bearing thereon will be allowed a vertical movement, it will be positively prevented from moving either sidewise or lengthwise.

Having described our invention, what we claim is—

1. The combination, with a railway and the cross-tie thereof beneath the rail-joints, of a

sustaining-bridge, sprung or bowed, a yoke embracing the said tie, and nuts for adjusting the same, substantially as specified.

2. The combination, with the sustaining-bridge having apertures, as described, to receive the yoke and nuts thereon, of the yoke having its ends threaded and adapted to embrace a cross-tie, and the nuts on the ends of the yoke, substantially as specified.
- 10 3. As an improved article of manufacture, a sustaining metallic bridge for application at rail-joints and for similar uses, constructed as

described, and bowed or sprung longitudinally, whereby the tie sustained by the yokes may be adjusted when depressed by use, substantially as specified. 15

In testimony whereof we affix our signatures in presence of two witnesses.

WILLIAM LYON.
JOHN B. GORRELL.
